UNITED STATES PATENT OFFICE

ADOLPH L. DE LEEUW, OF PLAINFIELD, NEW JERSEY, ASSIGNOR TO GOTHAM KNITBAC
MACHINE CORPORATION, OF NEW YORK, N. Y., A CORPORATION OF DELAWARE

FABRIC REPAIRING APPARATUS

Application filed February 16, 1929. Serial No. 340,488.

This invention relates to apparatus for repairing fabrics, and more particularly for repairing runs, ravel, dropped stitches, and the like in knitted goods, such as hosiery, underwear, and similar articles.

An object of the invention is to provide an apparatus for repairing fabrics which is simple in structure, economical to manufacture, and efficient in operation.

10 A further object of the invention is to provide an apparatus of the nature referred to which is strong, rugged, and durable and which eliminates many parts heretofore employed in machines of this nature.

15 A further object of the invention is to provide means in a machine of the character referred to for securing and maintaining a proper proportionate relation of pressures of the devices concerned in maintaining the fabric in position while the apparatus is in operation.

20 A further object of the invention is to provide means for adjusting the initial position of the needle carrying bar when in its normal inactive position.

25 A further object of the invention is to provide an improved structure for operating the needle carrying member, in order to simplify such structure and to automatically compensate for any deviation in the line of movement of the connections employed for operating the needle carrying bar in securing a rectilinear movement of said bar.

30 A further object of the invention is to simplify and improve the structure of feed mechanism employed for advancing the work during the operation of the apparatus, and to render the same strong and durable.

35 A further object of the invention is to provide an actuating mechanism for the work feeding devices which is simple and efficient and which avoids variations produced by accurate movement of parts of the mechanism.

40 Other objects of the invention will appear more fully hereinafter.

The invention consists substantially in the construction, combination, location and relative arrangement of parts, all as will be more fully hereinafter described, as illustrated in the accompanying drawings, and

finally pointed out in the appended claims.

In the accompanying drawings—

Figure 1 is a view in side elevation, parts in vertical longitudinal section, of a structure of fabric repairing apparatus embodying and containing features of my invention;

Fig. 2 is a view in section on the line 2—2, Fig. 1, looking in the direction of the arrows;

Fig. 3 is a broken detail view in section on the line 3—3, Fig. 1, looking in the direction of the arrows;

Fig. 4 is a broken detail view in side elevation, partly in vertical section, showing the relation of the needle and its supporting bar 65 and associated presser devices;

Fig. 5 is a broken detail view in section on the line 5—5, Fig. 4, looking in the direction of the arrows;

Fig. 6 is a view in horizontal section on the line 6—6, Fig. 1, looking in the direction of the arrows;

Fig. 7 is a broken detail view in section on the line 7—7, Fig. 1, looking in the direction of the arrows, but including the bearings of 75 the main drive shaft of the machine;

Fig. 8 is a broken detail view, parts in section, illustrating a structure of ratchet feed mechanism embodying the principles of my invention for actuating the work feeding devices;

Fig. 9 is a broken detail view illustrating the relation of the feed actuating pawls and their associated ratchets;

Fig. 10 is a detail view in section on the line 10—10, Fig. 1, looking in the direction of the arrows;

Fig. 11 is a broken detail view in horizontal section through the fulcrum mounting of the lever for actuating the feed devices, the actuating lever being omitted;

Fig. 12 is a broken detail view in horizontal section on the line 12—12 Fig. 1, looking in the direction of the arrows;

Fig. 13 is a view in side elevation of the machine, the lower part of the machine and its stand being broken off, and

Fig. 14 is a similar view in top plan of the structure shown in Fig. 13.

The same part is designated by the same 100

reference numeral wherever it occurs throughout the several views.

In the application of Leavin and Leavin, Serial No 248,806, filed January 23, 1928, 5 patented April 9, 1929, as No. 1,708,675, and the application of Raymond L. Plumley, Serial No. 296,968, filed August 2, 1928, patented April 9, 1929, as No. 1,708,681, there are shown, described, and claimed structures of 10 apparatus for repairing fabrics, particularly designed for use in repairing runs, dropped stitches, and the like in knitted fabrics. The present invention relates generally to apparatus of this type, and is designed to improve 15 the structures of the Leavin and Plumley machines in various particulars, for the purpose of simplifying said structures, rendering them more sturdy and rugged and efficient in operation, and to avoid the necessity 20 for readjusting various parts to adapt the machine for operation on fabrics of relatively different mesh.

Generally stated, machines of this class comprise a suitable stand or frame indicated 25 at 15 having laterally extending arms 16, 17. The arm 16 carries the needle bar and presser devices, and also the lever by means of which the needle bar is actuated, while the arm 17 carries the fabric or work feeding and thread 30 spacing devices, as well as the actuating lever therefor. The actuating levers for the needle bar and the work feeding devices, are operated from a main drive shaft which is journaled in the main frame of the machine. 35 In general, these are features common to the Leavin and Plumley machines.

One feature of improvement contemplated 40 by my invention to which I will refer, relates to the structure, mounting, connections and operation of the lever through which the needle bar is operated.

Suitably journaled in the frame of the machine, preferably, though not necessarily in anti-friction bearings 18, is the main power 45 shaft 19. This shaft is adapted to receive power from any suitable or desired source. Upon shaft 19 is mounted an eccentric member 20, which is engaged by a strap 21, having an arm to which is pivotally attached one 50 end of a needle bar actuating lever 22. The needle bar 23, is mounted at the free or head end of the frame arm 16, to slide rectilinearly in bearings therefor. The needle 24 is mounted in any suitable or convenient manner up- 55 on the needle bar 23. The needle bar is formed with a squared or planed portion 25, see Fig. 6, having oppositely presenting tapering seats 26 formed in the opposite faces thereof. The forward end of the lever 22 is 60 forked to straddle the squared or planed portion of the needle bar 23, the two arms of the fork each carrying a center plug 27 having a tapered end which fits into the tapered seat in the adjacent surface of the needle bar. 65 This structure affords a connection between

the needle bar and its actuating lever which permits a relative rocking movement of the lever with respect to the needle bar, while at the same time avoiding the necessity of a close fit between these parts. This enables 70 the various parts to be readily and easily assembled, or disassembled, and avoids expensive machining operations to secure accuracy in the manufacture of the individual parts, thereby greatly reducing the cost of construction, while at the same time securing easy and 75 smooth operation of the machine in use.

In the structure shown as an exemplification of my invention the needle bar 23, in operation, is caused to move longitudinally 80 and in a straight line, being so compelled by the aligned bearings through which it slides. In this structure when the needle bar actuating lever 22 is rocked by the eccentric and strap connections thereto, the end thereof 85 which is connected to the needle bar 23 must likewise move in a straight line, with the needle bar. This requires that the end of said lever which is connected to the eccentric strap shall move in an arcuate path when the machine is in operation. This arcuate movement is permitted by the journaling of the strap upon the eccentric, and the pivotal connection of the lever end with the strap arm.

By reason of the fact that one end of the needle bar operating lever must move in a straight line with the needle bar while the other end of said lever describes an arcuate movement in operation, the fulcrum point of said lever cannot be stationary but must be 95 permitted to shift. To accomplish this I provide a fulcrum structure for the needle bar operating lever which will permit an endwise or longitudinal movement of the lever relatively to its fulcrum, thereby causing the fulcrum point of the lever to shift during the rocking movements of the lever. One means for accomplishing this result is shown wherein the lever 22 is provided with an elongated slot 28, in which is received a 100 block, which, in the form shown, and for convenience in assembling, consists of two 105 oppositely disposed sleeves 29, see Figs. 1 and 6, mounted upon the portion 30 of a stud shaft 31 which is rotatively mounted in bearings 110 in the arm 16 of the frame. 115

By this arrangement it will be seen that the lever 22 is permitted not only its needle bar operating rocking movement but also longitudinal shifting movement necessitated by the fact that one of its ends is required to move in a straight line while its other end moves in an arc. The arrangement described also permits the rocking movement of the lever, as the fulcrum block 28, may swivel on 120 the portion 30 of the supporting shaft 31. 125

In the use of a machine of the class to which my invention relates it is customary to move the needle and its supporting bar to a position beyond the limit of its reciprocatory 130

movement when in use, so as to leave ample space to enable the work to be properly positioned in the machine. I have provided a simple arrangement for accomplishing this purpose, wherein I form the portion 30 of the stud shaft 31 eccentrically with respect to the longitudinal axis of said stud shaft. As above explained, this portion of the stud shaft forms a support for the fulcrum block 29. Therefore, by rotatively moving the stud shaft 31 in its bearings in the side walls of arm 16, the fulcrum block is raised or lowered as the case may be, thereby rocking lever 22 about its point of hinge connection 29 with the arm of strap 21, and hence correspondingly raising and lowering the needle bar 23. The stud shaft may be rotatively displaced in any suitable or convenient way. In the arrangement shown a crank arm 32, see Fig. 13, on the projecting end of the stud shaft, is provided for this purpose. By rotating the stud shaft through 180° , from its normal position when the machine is in operation, the needle bar is raised sufficiently to permit the work to be properly positioned in place in the machine. By restoring said stud shaft to its initial position the needle bar is returned to its normal working position.

30 In machines of the nature and class to which the present invention relates, it is customary to employ presser devices designed and arranged to press and hold the work under the desired tension, while the repair operation is being performed, and while the feed of the work is being accomplished. Such presser devices may be of any suitable or desired structure, and they are positioned above the head or saddle over which the work is placed and fed while being repaired. They are also mounted in such relation to the needle and the work feeding and thread spacing devices as to co-operate therewith to efficiently retain and hold the work in position, and to assist in maintaining the desired tensioning and feed of the work, and the desired spacing apart of the successive threads which cross the run to be repaired, to enable the repairing operations to be carried out successfully, rapidly and neatly.

In accordance with my invention I provide a presser device structure which is simple and efficient and which, in the illustrative form shown, consists of a spring presser foot 33, and, in addition, one or more presser rolls 34. The presser foot 33 consists of spring arms which, respectively, extend, at the free ends thereof, to points closely adjacent but on opposite sides of the point where the needle acts upon the work in effecting the repair. The function of these spring presser arms is to press the work flatwise upon the saddle and upon the spacing and feeding devices, and under suitable but yielding tension, at the point of action of the needle. The presser

roll, or rolls 34 are disposed beyond the presser feet and are designed to press and hold the work in efficient engagement with the surface of the feeding and spacing devices. In the drawings I have shown two 70 presser rolls, or a single roll having two cylindrical portions, see Fig. 2, the peripheral surface of which is serrated to more efficiently cooperate with the serrated surface of the fabric or work feeding devices 35. 75

It is important that both of the presser roll portions 34 bear upon the work with the same degree of pressure. It is likewise important that both of the arms of the spring presser foot 33, bear upon the work with the same degree of pressure and that the pressure of the presser foot with relation to that of the presser roll be maintained at a substantially uniform ratio. The importance of these requirements will be understood when it is realized that a slight unevenness in the goods, such, for example, as a little knot or kink in the surface of the fabric passing beneath the presser foot, or one or the other arms thereof, or beneath the presser roll, might disturb the evenness of the feed of the fabric or work, or the proper and regular spacing apart of the threads across the run to be repaired, thereby impairing the neatness of or creating a fault in the repair being made. This same difficulty is likewise liable to occur where each of the two arms of the spring presser foot is separately mounted and independently adjustable as to the pressure which it exerts. In such case, the proper equalization of the pressures of the two spring arms is dependent upon the accuracy with which the operator, often unskilled, is able to adjust each of the two arms. To obviate these and other difficulties, and to greatly simplify the mechanical structure, and to eliminate unnecessary parts, I propose, in accordance with my invention, to employ a single presser bar 36, which, in the arrangement shown, is mounted to slide in the head end of the arm 16 of the framework, adjacent to and parallel with the needle bar. The presser bar 36 may be prevented from turning axially in its bearings in the head of arm 16. This may be accomplished in any convenient manner, as, for example, by means of a key 37. An adjustable spring tension is imposed upon the presser bar in various ways to yieldingly press the presser roll and presser foot to their respective engagements with the fabric or work. This tension is secured in the present instance, by means of a coiled spring 38, interposed between a shoulder 39 on the presser bar and the end of an adjustable bushing 40, screwed into the arm 16, and through which the presser bar extends, see 110 Figs. 1 and 2.

A block 42 is pivotally connected to the lower end of the presser bar, for slight rocking movement relatively thereto. A simple 130

arrangement is shown wherein the lower end of the presser bar is slotted, as indicated at 41, and a portion of the block 42 extends into the slot and is held therein by the pivot pin 43. The extent of the rocking movement of block 42 is determined by the clearance between the same and the bottom of the slot 41. Of course, it is to be understood that many other expedients may be equally suitable for this purpose. Pivottally mounted upon the block 42 is another member 44, by means of a pivot pin 45. The axis of the pivot pin 45 is in right angular relation with respect to that of the pivot pin 43. The member 44 has a seat 46 in which is received and pivottally supported the end portion of the spring presser foot, a sufficient clearance being provided in the seat to permit slight angular rocking motion of the presser foot upon its pivot pin 47. An arm 48 of member 44, carries the presser roll 34.

From this description it will be seen that the block or member 44 forms a support for the presser foot and also for the presser roll. Also, that not only has the block or member 44 a rocking movement in two directions at right angles to each other, because of the relation of the pivot pins 43 and 45, but the presser foot 33 has a slight independent side 30 rocking movement with relation to block 44 upon its own pivot 47. It will also be seen that according to the relative distances of the presser roll 34, and of the work engaging portions of the arms of the presser foot, 35 from the longitudinal center line of their common supporting bar 36, there is maintained a substantially constant proportional pressure of said roll and presser foot upon the fabric or work, and this proportional relation is not altered or changed by the adjustment of the presser bar itself. It will also be seen that the structure described provides for the proper distribution of the pressures exerted by the roll and the presser foot, 40 while at the same time ensuring that both parts of the presser roll as well as both arms of the presser foot, press evenly against the goods or fabric.

In positioning the fabric or work to be repaired in the machine it is necessary to remove the presser roll and presser foot, as well as the needle out of the way. I have already described means for raising the needle bar. The presser bar may, in like manner, 55 be raised out of the way, to permit the work to be placed in position to be operated, and this can be accomplished in various ways, either by hand or foot. In Figs. 13 and 14 I have shown a lever 49, pivottally mounted 60 on the arm 16 of the frame and having its free end engaged beneath a pin 50 carried by the presser bar 36. By rocking the free end of said lever upwardly the presser bar, carrying the presser roll and presser foot is 65 raised sufficiently to permit the work to be

placed in position in the machine. The lever 49 may be rocked by foot treadle (not shown) or by a hand lever 51, having a pin 52, engaging beneath said lever 49.

In the practical operation of machines of this class it is exceedingly important that the feed of the work be accomplished smoothly and evenly and in the proper timed relation with respect to the operation of the needle. It is equally important that the threads which cross the run to be repaired be efficiently spaced apart from each other to ensure the needle successively operating upon each succeeding cross thread of the run in making the repair. The extreme accuracy required in these operations has heretofore necessitated the employment of delicate parts which require the utmost care in their manufacture, and in the assembly thereof, and which, by reason of their delicate nature lack sturdiness and strength, and are liable to wear rapidly and to break and thereby requiring frequent renewals and repairs. Commonly, such structures have heretofore required the use of a pair of main feed rolls for the work which are rotatively actuated one space at a time by means of a ratchet wheel disposed between them. The spacing apart of the main feed rolls is limited by the fineness or coarseness of the weave or mesh of the fabric or work. In practice the required spacing referred to ranges from thirty nine one-thousandths of an inch down to thirty three one-thousandths, according to the character of the mesh or weave of the fabric, so that even for the coarser weaves or meshes of fabric the distance of separation of the feed rolls, and hence the space available for accommodating the actuating ratchet wheel, is necessarily very small. Moreover, as the needle in accomplishing its work must penetrate into this space, the available diameter of the ratchet wheel is likewise prescribed and limited. By reason of these limitations the ratchet wheel, heretofore has been exceedingly thin and frail, and the ratchet teeth thereof had to be cut very small, thereby making each tooth not only very narrow and weak, but the spacing between the teeth very fine. In operation the needle frequently produces a certain amount of very fine lint which often drops into the space between the feed rolls and fills the teeth of the ratchet wheel, thereby interfering with the proper engagement therewith of the operating pawls and causing trouble. It is among the special purpose of my present invention to provide a structure of feed mechanism which obviates these and other objections, and whereby a strong durable and rugged structure is produced.

In carrying out my invention, in one practical embodiment thereof, I employ two ratchet wheel 53, placed respectively at the outer sides of the two feed rolls 35, see Fig. 130

12. By so placing the ratchet wheels I am not prescribed as to their thickness, and, consequently, they may be constructed of substantial thickness to make them strong and sturdy in use. Instead of providing each ratchet wheel with the number of teeth which would be required if only one such ratchet wheel is employed, I form each one with only one-half such number of teeth. I 5 am thus enabled to make the spacing between the teeth twice as great, and to construct such teeth of substantial proportions and size as to render them strong and sturdy. While the two ratchet wheels are provided with the 10 same number of teeth, they are, however, mounted in rotatively displaced relation with respect to each other a distance of substantially one-half the space between two adjacent teeth, as clearly shown in Fig. 9.

20. Cooperating with each ratchet is a pawl 55. These pawls are of the same length and they advance to their work simultaneously and for the same length of stroke. By reason of the displaced relation of the two ratchets only 25 one pawl is acting on one forward stroke, the other pawl acting on the next succeeding forward stroke. On each return stroke the pawl which was idle on the forward stroke snaps behind a tooth on its associated ratchet ready 30 to carry on the rotative feed movement of the feed wheels on the next forward stroke. To ensure this action the strokes of the pawls should be slightly greater in length than one-half of the space between two adjacent ratchet teeth but less than one full space.

It is a common practice to operate the feed 35 wheel actuating pawls in machines of this class by means of an eccentric on the main drive shaft of the machine, which actuates 40 a lever connected to the pawls. With this eccentric drive structure it is evident that during one-half of a revolution of the main shaft the pawls are being moved in one direction of stroke and during the other half 45 they are being moved in the opposite direction. The feed of the work, however, must be accomplished during approximately only one-quarter of a revolution of the main shaft to secure the timing operations necessary in 50 the operation of the machine. Consequently, the movement of the pawls is twice as great as can be usefully employed.

In order to avoid this useless movement, 55 which would destroy the proper timing of the feed, I dispense with the eccentric, and in place thereof mount a disk member 56, on the main drive shaft 19, in one face of which is formed a cam groove 57, see Figs. 3, 6 and 7, in which groove works a roller 58, carried 60 by an arm 59. To the free end of this arm is pivotally connected one end of a lever 60. The arm 59 straddles the main shaft 19, and hence is held against rocking movement, while being operated in a rectilinear longitudinal direction. The cam groove 57 is so

shaped that during one-quarter of the revolution of the main shaft 19, the lever 60 is rocked to actuate the pawls in one direction, and during another quarter of such revolution said lever is rocked to actuate the pawls 70 in the opposite direction, the said lever being held stationary during the remainder of the revolution of the main shaft. This affords an additional safeguard against back lash or the working backwards of the feed rolls while the needle is performing its work. The free end of lever 60 is pivotally connected to one arm of a bell crank lever 61, to the other arm of which the two pawls 55 are pivoted. The 75 rocking motions imparted to the bell crank 61, by the lever 60, causes the required forward and backward movement of the pawls to effect the actuation of the feed rolls. The bell crank lever 61 is pivoted upon a stud 62, mounted in the arm 17 of the frame, and 80 pivotally mounted on the same stud are the retaining pawls 63, which coact with the ratchet wheels 53 to prevent retrograde movement thereof. A spring 64 interposed between the retaining pawls and an extension of the ratchet pawls, see Fig. 8, holds the engaging ends of said pawls in engagement 85 with the teeth of the ratchet wheels.

The spacing apart of the threads which cross the run in a fabric or article to be repaired is accomplished by means of spacer disks 65, having peripheral teeth which engage the successive run crossing threads and uniformly space them apart to enable the needle to pass between the successively adjacent threads in the performance of its work of forming a loop in each succeeding thread and interengaging the successive loops. These spacing disks are assembled with the feed rolls 35 and ratchet wheels 53 into a compact unitary structure, all these parts being mounted on the same supporting rod 66, which is mounted in the side portions of frame arm 17, see Fig. 12, and are secured together by the bolts 67. The spacer disks 65 are disposed at the inner faces of the feed wheels 35, and are spaced apart from each other by means of an interposed plate 68 of reduced diameter to permit the needle to be projected into the space between the spacer disks. A simple compact and efficient assembly of the work feeding and spacing unit is secured by providing the spacer members 65 with hub extensions 78, upon which the feeding members 35, are mounted, the ratchet members 53, as above explained, lying against the outer faces of the feeding members. This makes a very strong, durable, sturdy and compact unit assembly.

In practice the mesh or weave of fabrics which are to be repaired vary, that is, some fabrics are of finer mesh or weave than others. To illustrate, some fabrics have a fine mesh of, say, 280, that is it has 280 threads per unit of length, while others have a coarser

mesh, of say, 248. This means that in the one case the spacer disks should have 280 peripheral spacing teeth, while in the other only 248 are required. While it is not essential that the number of spacing teeth on the spacer disks shall correspond accurately with the mesh of the fabric to be repaired, nevertheless, it is not practical nor desirable to employ the same spacing disks, or spacing 10 disks having the same number of spacing teeth, or the same feeding ratchets, or ratchets having the same number of teeth for all the various grades of mesh which occur. It is, therefore, necessary to so construct the 15 feed unit assemblies that they may be readily and easily removed and replaced by another to accord approximately with the mesh of a different fabric to be repaired. While the removal and replacement of feed head 20 assemblies has been proposed heretofore, various difficulties have been encountered by reason of the necessity for various adjustments of the parts and retiming of the same so as to coordinate properly the substituted 25 head with other parts of the mechanism. Where such replacement is made by unskilled operators the failure to make the proper timing and other coordinating adjustments invites trouble. The principal coordination 30 required, in replacing a feed head is that of the length of stroke of the pawls 55, it being understood, of course, that there is correspondence between the number of ratchet teeth and the number of spacer teeth for any 35 given mesh of fabric. Take, for example, the same illustration as that given above, where a fabric having a 280 mesh is first repaired and then one having a 248 mesh is to be repaired on the same machine. In that case 40 two different heads will be used, namely, one with provision for 280 spaces for the finer mesh fabric, and then this one replaced with another head having provision for 248 spaces for the coarser fabric. When the change of 45 heads is made it becomes necessary to vary correspondingly the length of stroke of the feed actuating pawls 55. If the change is made from a 280 spacing head to a 248 spacing head the working stroke of the pawls must be increased. If the change is from a 248 to a 50 280 spacing head the working stroke of the pawls must be decreased. To effect this variation quickly, easily and without any special skill I form an elongated slot 69 in pawl operating lever 60. Transversely through this 55 slot extends a fulcrum block 70, which has a sliding connection with the lever. This block is carried by an eccentric portion 71, see Figs. 10 and 11, of a transversely extending shaft 72, suitably journaled at its ends in the side walls of the frame arm 17. This constitutes a movable fulcrum for the lever 60, which fulcrum divides the lever into two arms. On the ratio of the lengths of these 60 two arms depends the amount of stroke that

is to be given to feed actuating pawls 55. When the eccentric portion 71 is turned to a position to carry the fulcrum block 70 to the left as viewed in Fig. 10, the left-hand end of the lever 70 becomes shorter and the right hand end becomes longer, reckoning from the fulcrum point. This results in increasing the length of stroke of the pawls. Similarly, when the eccentric portion 71 is turned to a position to carry the fulcrum block towards the right the reverse of this action takes place. The eccentricity of the fulcrum block support is so calculated that its left-hand limit position corresponds to a 248 space head while its right-hand limit position corresponds to a 280 space head. Any desired intermediate position will take care of the corresponding spacing intermediate the limits stated. The shaft 72, may be rotatively adjusted to accomplish the variation in length of stroke of the feed actuating pawls, as above explained. This adjustment may be effected in many different ways. A simple arrangement is shown which can be readily manipulated by even the most unskilled operator, wherein a knob 73 is keyed to the pin or shaft 72 to slide thereon to a limited extent. This knob is permitted to slide axially of the pin or shaft 72 against the tension of a spring 74, and it carries a pin 75, adapted to snap into one or another of spaced holes 76. By simply pulling out the knob and turning it and the pin or shaft 72, so as to bring the pin 75 into register with the proper hole 76 the desired adjustment is effected. 100

To remove and replace a feed head unit the cover plate 77 is removed, and the end screws which hold the pin 66 in place are removed. The pin is then pushed out and the entire feed head unit drops out. 105 The head to be substituted is then inserted in place, the pin 66 is restored and fastened and the cover plate applied. In order to facilitate the removal and replacement of heads it is desirable to remove the tension spring 64 from between the pawls 5 and 63. Thereupon these pawls swing out of the way by gravity. In replacing the spring 64, the pawls are arrested in their movement under the action of the 110 spring by limit stops 79. If desired the spring 64, need not be removed at all as the stop pins 79 may be sufficient to prevent the pawls from interfering with the removal and replacement of the feed heads. 115

While I have shown and described a structure illustrating one embodiment of my invention it is obvious that many changes in the details thereof may readily occur to persons skilled in the art and still fall within the spirit and scope of my invention. I do not desire, therefore, to be limited or restricted to the exact details shown and described. 120

But having now set forth the objects and 124

nature of my invention, and a structure embodying the principles thereof, what I claim as new and useful and of my own invention, and desire to secure by Letters Patent is—

5 1. In a fabric repairing apparatus, a reciprocating needle bar, an operating lever for reciprocating said bar, said bar having a planed portion with oppositely disposed tapered seats, a center plug for each seat carried by the lever to operatively engage said seats in said planed portion to effect pivotal connection between the lever and bar, and means to rock said lever.

10 2. In a fabric repairing apparatus, a reciprocating needle bar, an operating lever for reciprocating said bar, said bar having planed surfaces on the opposite sides thereof, said surfaces having seats formed therein, the free end of said lever being forked to straddle said bar, the forked ends of the lever carrying center plugs to pivotally engage in said seats, and means to rock said lever.

15 3. In a fabric repairing apparatus, a reciprocating needle bar, an operating lever for reciprocating said bar, said bar having planed surfaces on opposite sides thereof, said planed surfaces having tapered seats formed therein, the free end of said lever being forked to straddle said bar, center plugs carried by the fork ends of said lever, said plugs having pointed ends to be received in said seats to form pivotal connections between the lever and bar, and means to rock said lever.

20 4. In a fabric repairing apparatus, a needle bar mounted to slide rectilinearly in aligned bearings, an operating lever pivotally connected at one end to said bar, a main drive shaft, an eccentric carried thereby, a strap mounted on said eccentric and pivotally connected to the other end of said lever, and a movable fulcrum block for said lever, said block having flanges slidably engaging said lever.

25 5. In a fabric repairing apparatus, a needle bar mounted to slide rectilinearly in aligned bearings, an operating lever pivotally connected at one end to said bar, a main drive shaft, an eccentric carried thereby, a strap mounted on said eccentric and pivotally connected to the other end of said lever, a fulcrum block upon which said lever rocks, and means to permit relative sliding movement of the lever and fulcrum block during the operation of the lever.

30 6. In a fabric repairing apparatus, a needle bar mounted to slide rectilinearly, an operating lever pivotally connected at one end to said lever, said bar having an elongated slot, a pivotally mounted fulcrum block, arranged to extend through said slot, said block mounted slidably in said slot, and means pivotally connected to said lever to rock the same.

35 7. In a fabric repairing apparatus, a

needle bar mounted to reciprocate rectilinearly, an operating lever pivotally connected at one end to said needle bar to reciprocate the same, actuating means for said lever to rock the same, a pivotally mounted fulcrum block for said lever, said lever having an elongated slot extending longitudinally thereof, said block engaging in said slot whereby said lever is permitted endwise movement while it is being rocked.

70

8. In a fabric repairing apparatus, a needle bar, an operating lever connected thereto, and means to actuate said lever, in combination with a movable eccentric arranged to engage said lever to raise the needle bar beyond the limit of its operating movement when in use.

75

9. In a fabric repairing apparatus, a needle bar, an operating lever connected thereto, and means to actuate said lever, in combination with a rotatably adjustable stud shaft, and an eccentric thereon arranged to engage said lever, whereby said lever may be raised to elevate the needle bar beyond the limit of its operating movements.

80

10. In a fabric repairing apparatus, a needle bar, an operating lever connected thereto, and means to actuate said lever, in combination with a fulcrum block for said lever, and a rotatably adjustable stud shaft having an eccentric portion upon which said fulcrum block is mounted, whereby when said stud shaft is rotatably adjusted the needle bar is raised beyond its limit of operating movement.

95

11. In a fabric repairing apparatus, a needle bar, an operating lever connected thereto, and means to actuate said lever, in combination with a rotatably adjustable stud shaft, and an eccentric thereon arranged to engage said lever, whereby said lever may be raised to elevate the needle bar beyond the limit of its operating movements, and an operating arm on said stud shaft to rotatably adjust the latter.

100

12. In a fabric repairing apparatus, and in combination with work feeding and spacing mechanism, presser devices including a presser foot and a presser roll, a single supporting bar for said foot and roll, said foot and roll having pivotal connections in intersecting directions with said support.

105

13. In a fabric repairing apparatus, and in combination with work feeding and spacing mechanism, presser devices including a presser foot and a presser roll, a single supporting bar for said foot and roll, said presser foot having pivotal movements laterally and other movements at an angle with respect to said support.

110

14. In a fabric repairing apparatus, and in combination with work feeding and spacing mechanism, a supporting bar, a block pivotally connected to said bar, a presser roll and a presser foot having pivotal con-

115

120

125

130

nection with said block, the axes of said pivotal connections being in intersecting planes.

15. In a fabric repairing apparatus, and in combination with work feeding and spacing mechanism, a supporting bar, a block pivotally connected to said bar, a member pivotally connected to said block, said member having a seat formed therein, a presser roll carried by said member and a presser foot pivotally mounted in said seat.

16. In a fabric repairing apparatus, and in combination with work feeding and spacing devices, a supporting bar mounted for longitudinal, but held against rotative movement, a presser roll and a presser foot carried by said bar and arranged to extend in opposite directions therefrom, a spring engaging said bar to yieldingly press said roll and foot to their work, and means to adjust the tension of said spring.

17. In a fabric repairing apparatus, and in combination with a needle and its operating mechanism, work feeding and spacing devices, including a head unit assembly having spacing and feeding members, and an operating ratchet to rotatively actuate the same, the operating ratchet being disposed at the outer side of the feeding members.

18. In a fabric repairing apparatus, and in combination with a needle and its operating mechanism, work feeding and spacing devices, including a head unit assembly having spacing and feeding members, the spacing members being spaced apart from each other, and the feeding members disposed outside the spacing members, and a ratchet member disposed outside of the feeding members.

19. In a fabric repairing apparatus, and in combination with a needle and its operating mechanism, work feeding and spacing devices, including a head unit assembly having spacing and feeding members, the spacing members being spaced apart from each other, and the feeding members disposed outside the spacing members, a ratchet member disposed outside of the feeding members, all of said parts being secured together and rotatable as a unit.

20. In a fabric repairing apparatus, and in combination with a needle and its operating mechanism, work feeding and spacing devices, including a head unit assembly having spacing and feeding members, the spacing members being spaced apart from each other, and the feeding members disposed outside the spacing members, and ratchet members disposed outside of the feeding members in the unit assembly.

21. In a fabric repairing apparatus, a work feeding and spacing unit assembly including feeding, spacing and actuating ratchet members the ratchet members each having one-half the number of teeth of the spacing members, and operating pawls cooperating with said ratchet teeth.

22. In a fabric repairing apparatus, a work feeding and spacing unit assembly including feeding, spacing and actuating ratchet members the ratchet members each having one-half the number of teeth of the spacing members, operating pawls cooperating with said ratchet teeth, said pawls acting alternately on said ratchets to rotatively move the same one-half a tooth space at each actuation thereof.

23. In a fabric repairing apparatus, a work feeding and spacing unit assembly including feeding, spacing and actuating ratchet members the ratchet members each having one-half the number of teeth of the spacing members, operating pawls cooperating with said ratchet teeth, said ratchets being rotatively displaced a distance of one-half a tooth space with reference to each other.

24. In a fabric repairing apparatus, a work feeding and spacing unit assembly including feeding, spacing and actuating ratchet members the ratchet members each having one-half the number of teeth of the spacing members, operating pawls cooperating with said ratchet teeth, said ratchets being rotatively displaced a distance of one-half a tooth space with reference to each other, said pawls acting alternately on said ratchets to rotatively move the same a distance of one-half a tooth space at each actuation thereof.

25. In a fabric repairing apparatus, a removable and replaceable work feeding and spacing unit assembly, including toothed spacing and toothed ratchet members, whereby one such unit may be replaced by another having a different number of spacing and ratchet teeth according to the mesh or weave of the work fabric, an actuating pawl for the ratchet member, and means to vary the stroke of the actuating pawl to correspond with the number of teeth of the ratchet member of the unit.

26. In a fabric repairing apparatus, a removable and replaceable work feeding and spacing unit assembly including a toothed ratchet member, in combination with an actuating pawl for said ratchet member, means to operate said pawl, and means to vary the stroke of said operating means to correspond with the number of teeth of the ratchet member.

27. In a fabric repairing apparatus, a removable and replaceable work feeding and spacing unit assembly including a toothed ratchet member, in combination with an actuating pawl for said ratchet member, a rocking support for said pawl, a lever to rock said support, and means to adjustably vary the leverage of said lever.

28. In a fabric repairing apparatus, a removable and replaceable work feeding and spacing unit assembly including a toothed ratchet member, in combination with an actuating pawl for said ratchet member, a piv-

oted lever to operate said pawl, and means to adjust the fulcrum of said lever to vary the working stroke of the pawl.

29. In a fabric repairing apparatus, a removable and replaceable work feeding and spacing unit assembly including a toothed ratchet member, in combination with an actuating pawl for said ratchet member, a lever to operate said pawl, a rotatably adjustable pivot stud for said lever, said stud having an eccentric portion to constitute the fulcrum for said lever, whereby, by rotatably adjusting said stud the fulcrum of the lever is shifted to vary the working stroke of the pawl.

30. In a fabric repairing apparatus, a removable and replaceable work feeding and spacing unit assembly including a toothed ratchet member, in combination with an actuating pawl for said ratchet member, a pivoted lever to operate said pawl, a movable fulcrum for said lever, and means to adjust said fulcrum.

31. In a fabric repairing apparatus, a removable and replaceable work feeding and spacing unit assembly including a toothed ratchet member, in combination with an actuating pawl for said ratchet member, a lever to operate said pawl, said lever having a longitudinal slot therein, a movable fulcrum member engaging in said slot, and means to adjust the fulcrum member to vary the working stroke of said lever.

32. In a fabric repairing apparatus, a work feeding and spacing unit assembly including a ratchet member, in combination with an actuating pawl and a holding pawl for said ratchet member, and means for actuating the same, and a spring interposed between said pawls, and arranged to exert its tension upon both pawls to hold them in engagement with said ratchet member.

33. In a fabric repairing apparatus, a work feeding and spacing unit assembly including a ratchet member, in combination with an actuating pawl and a holding pawl for said ratchet member, means for actuating the same, a spring interposed between said pawls, and arranged to exert its tension upon both pawls to hold them in engagement with said ratchet member, and stops to limit the extent of movement of said pawls under the action of said spring.

34. In a fabric repairing apparatus, a work feeding and spacing unit assembly including a ratchet member, in combination with an actuating pawl and a holding pawl for said ratchet member, a rock member upon which said pawls are pivotally mounted, a limit stop on said rock member for each of said pawls, a spring arranged to act on both pawls to press them towards their limit stops, and means to rock said rock member.

35. In a fabric repairing apparatus, a reciprocating needle bar having a seat formed

therein, an operating lever for said needle bar, and a pivot member carried by said lever and engaging in said seat to pivotally connect said lever and bar.

36. In a fabric repairing apparatus, and in combination with a needle and needle bar, and means to operate said bar, of fabric feeding and spacing devices, and actuating mechanism therefor, including a drive shaft, a disk driven by said shaft and provided with a cam groove, and an arm held against oscillatory movement and having engagement in said cam groove whereby said arm is rectilinearly reciprocated.

37. In a fabric repairing apparatus, and in combination with a needle and needle bar, means to operate said bar, of fabric feeding and spacing devices, and actuating mechanism therefor, including ratchet pawls, a rock lever for operating said pawls, an arm pivotally connected to said lever and mounted to reciprocate but held against oscillatory movement, a rotatably mounted disk having a cam in the face thereof, and a stud carried by said arm and arranged to engage said cam.

In testimony whereof I have hereunto set my hand on this 11th day of February A. D. 1929.

ADOLPH L. DE LEEUW.
